Primary Examiner—Cathy Anne MacCormac
Attorney, Agent, or Firm—Oliff & Berridge, PLC[57] **CLAIM**

The ornamental design for ring, as shown and described.

DESCRIPTION

FIG. 1 is a top plan view of a ring showing my new design, the side view is substantially identical to FIG. 4 except for the finish of the band;

FIG. 2 is a front view thereof;

FIG. 3 is a rear view thereof; and,

FIG. 4 is a side view of a second embodiment of FIG. 1, the top, front and rear are substantially identical to FIGS. 1, 2, and 3 except for the shiny finish of the band.
